Kevin Prince(57) **CLAIM**

The ornamental design for a kettlebell handle, as shown and described.

DESCRIPTION

FIG. 1 is a perspective view of a kettlebell handle, showing my new design as fitted with weights partially broken away; FIG. 2 is a perspective view of FIG. 1, but with the weights omitted;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing weights in FIG. 1 depict environmental matter and form no part of the claimed design.
